UNITED STATES PATENT OFFICE.

DANIEL M. SCHIFFERT, OF BOSTON, MASSACHUSETTS, ASSIGNOR TO SEARS B. CONDIT, JR., OF BOSTON, MASSACHUSETTS.

ELECTRIC SWITCH.

1,393,836.

Specification of Letters Patent. Patented Oct. 18, 1921.

Application filed March 9, 1918. Serial No. 221,347.

To all whom it may concern:

Be it known that I, DANIEL M. SCHIFFERT, a citizen of the United States, residing in Boston, county of Suffolk, and State of 5 Massachusetts, have invented an Improvement in Electric Switches, of which the following is a specification.

My invention relates to switches or circuit breakers in which the contacts are 10 broken in air.

Electric switches adapted to automatically open upon an abnormal current condition in the circuit they are designed to control are commonly provided with means responsive to such abnormal condition to operate a latch or break a toggle to thereby cause the movable member of the switch to move to open position, usually under the influence of a spring.

20 If a latch is employed to normally restrain the movable switch member in the closed position of the switch, there is usually considerable pressure exerted upon the latch by the spring in such closed position 25 and a comparatively great force must be exerted upon the latch to move it to release the movable switch member, and consequently the tripping coil must be comparatively large and consume a comparatively 30 great amount of energy. The switches are, moreover, often arranged in sets to be simultaneously opened by a single trip coil and, because of the comparatively great amount of energy required to operate one latch, the 35 size of trip coil to simultaneously operate all the latches must be much greater than is considered permissible.

When a toggle member is employed in place of a latch to restrain the movable 40 switch member in closed position, the toggle is arranged to be slightly over shot in order that the switch may remain in closed position until opened. The electroresponsive tripping element is arranged, for the opening 45 of the switch, to move the toggle into and slightly beyond the straightened or on-center position, whereupon the movable switch member, being no longer restrained in closed position, may move to open position.

The toggle member, to restrain the switch 50 in closed position, also requires a comparatively great amount of energy to cause the switch to move to open position, because it must be moved from the over shot position into and beyond its straightened position. 55

A switch restrained in closed position by a latch is also very sensitive to mechanical shock or vibration. As there is a force constantly tending to move the switch to open position, any shock or jar to the switch 60 structure, such as may often occur in the operation of machines in proximity to the switch, often causes the latch to move the small amount necessary to release the movable switch member and the switch may 65 thereby be unnecessarily opened.

The toggle restrained switch is also subject to the same defect, as the over shooting of the toggle is usually made as small as possible in order that the switch may be 70 opened with but a small amount of energy.

The opening of the switch because of sudden jars or shocks is extremely undesirable, and may even cause considerable damage to apparatus connected to a circuit from which 75 uninterrupted power service is required.

Consequently an object of my invention is in the provision of an electrically controlled switch, in the closed condition of which there is no force acting upon the movable 80 member thereof to move said member into open position or into more fully closed position, whereby but a small amount of energy is required to condition the switch for movement toward open position. 85

A further object of my invention is in the provision of means to lock said switch in closed position against movement toward an open position whereby the switch will remain in such closed position until the operation of the tripping means, and will be unaffected by any jars or shocks to which it may be subjected. 90

The means whereby I accomplish these objects of my invention is in the provision 95 of a toggle member to restrain the switch in closed position and a latch to lock it in such position. In the closed position of the

switch the toggle is arranged to be in its straightened or on-center condition, and there is then no force acting upon the switch to move it toward an open position and but 5 a very slight effort is necessary to move the toggle the small distance required to permit the movable switch member to move into open position.

The locking latch is provided with a projection normally restraining the toggle from movement beyond straightened condition toward the open condition of the switch, and the switch structure is provided with abutments to prevent over shooting of the toggle 15 beyond the fully closed position of the switch.

The latch and abutment effectively prevent any movement of the toggle member and thereby securely hold the switch in closed 20 position. As the toggle is in its straightened condition or on center, but a slight effort is necessary to cause the switch to move to open position. The effect of any movement of the latch, due to vibrations or shocks, is 25 without effect on the switch because of the substantially on center position of the toggle, and the switch therefore remains positively in closed position until the tripping coil definitely operates the latch.

30 A further object of my invention is in the design of a switch that is relatively inexpensive in construction, and yet entirely substantial and reliable in operation.

The means whereby I accomplish the object 35 of my invention is in the construction of the switch mainly from stampings or punched parts, whereby the switches may be made in quantities with relatively small unit expense and may be, at the same time, substantial and rugged.

A yet further object of my invention is in the provision of a switch and tripping device therefor capable of being manufactured and assembled as separate units, and maintained 45 in stock as such for assembling in proper relation on switchboard.

Figure 1 is a side elevation of a switch and tripping device therefor embodying my invention.

50 Fig. 2 is a front elevation of the switch. Fig. 3 is a detail of the switch mechanism in open position.

Fig. 4 is a plan view of a switch contact member.

55 Fig. 5 is a sectional view of the contact member along lines 5—5 of Fig. 4.

Fig. 6 is a detail of the switch handle member.

Fig. 7 is a detail of the tripping coil and 60 terminal connection.

Fig. 8 is a modified form of latch.

As here shown, the switch is mounted on the switchboard 9, and comprises a housing formed of a single strip of material 65 flexed to provide the two parallel spaced

apart standards 10 between which the component parts of the switch mechanism is arranged, the supporting feet 11 and cross connecting strips 12. Said supporting standards are secured to the switchboard 9 by 70 means of screws 13 screwed into the strip 12 and by screw 14, in a manner hereinafter to be more fully described.

The movable switch arm, pivoted at 15 to the housing, comprises a single strip of 75 material so formed as to provide a channel section 16 in which the contact brush 17 is secured, extended arm portions 18 which are pivoted to the standards 10, and extended ears 19 by means of which connection is 80 made to the operating handle.

The contact brush 17 is of usual construction, and is arranged, in the closed position of the switch, to make contact with a stationary contact 20 mounted upon the switchboard. An auxiliary contact 21, also of common construction, is detachably secured to the resilient strip 22 carried by the switch arm, and is arranged to make contact with the auxiliary stationary contact 23. 85

A second auxiliary contact 24, formed of a carbon block, is connected with the stationary switch contact 20 and a second carbon block 25, secured to the resilient strip 26 carried by the movable switch arm, is arranged to make contact therewith in the closed position of the switch. 90

A spring strip 27 is secured to the movable switch arm, and its tip portion bears upon the resilient strip 26, whereby additional resiliency is imparted to the auxiliary carbon contact block carrier 26. Said brush member 17 and the resilient strips 22, 26 and 27 associated with the auxiliary contacts are all secured to the movable switch arm 105 by the bolts 28.

Switch operating links 29 are pivoted to the pin 30 extended between the ears 19 of the movable switch arm and at 31 to the switch handle member 32, which is pivoted 110 at 33 to the switch supporting standard. The links 29 and the switch handle member 32 form a toggle, by means of which the movable switch arm is moved between open and closed position. Said switch handle 115 member is composed of a single strip of material and formed with two spaced parallel arms 34 and the connecting portion 35, and is disposed between the supporting standards 10 upon the pin 33. One of the arms 34 of said member is formed with a cut out and reflexed portion 36 which, in the closed position of the switch, engages an edge of the supporting standards 10 and thereby forms an abutment to prevent further movement of the toggle mechanism beyond its on center or straightened position, and the abutment is so arranged that in the closed condition of the switch the toggle is on center. 120

The connecting portion 35 of the handle 130

- member is formed with a threaded opening 37 therein, and the handle 38 is provided with a bolt 39 which is screwed into this member, the said member and handle being locked against removal by the nut 40 secured to the end of said bolt 39.
- The parallel portions or arms 34 of the handle member are formed with extended ears 41, and a latch roller 42 is rotatably disposed therebetween on the pin 43.
- The latch, which comprises an object of my invention, and as shown in Figs. 1 and 3, is formed of two parts, a latch member 44 and a tripping member 45. Said latch and tripping members are arranged on a pin 46 between the standards 10 of the switch housing, and maintained in position on said pin by spacing washers or rollers 47. The latch member 44 is formed with an upright projection 48, which is arranged to engage with the latch roller 42 secured to the switch handle member in the closed position of the switch to maintain the movable switch member in such closed position.
- The latch member 44 is formed with an extension or projection 49 on the opposite side of the pin 46 over the upright extension 48, which is maintained in normal engagement with a projection 50 formed in the tripping member 45. A spring 51 coiled about the pin 46, and having its ends in engagement with one of said standards 10 and said latch member 44, serves to maintain the two portions of the latch in normal engagement.
- The tripping member 45 is formed with an end or nose portion 52, which is arranged adjacent the latch roller 42. When said tripping member 45 is moved upwardly under the action of the tripping means herein-after to be more fully described, said nose portion is arranged to engage the latch roller 42 to move the toggle members from their on center position to a position beyond center, to thereby permit the movement of the switch member into open position. The movement of the tripping member also serves to remove the latch member from engagement with the latch roller. The tripping member is extended from its pivot pin 46 to a point adjacent the pin 15 extended between the standards 10 of the switch housing, and is formed with two projections 53 which engage with said pin 15 to limit the movement of the tripping member.
- A modification of the latch is shown in Fig. 8, in which the latch member and the tripping member are integrally formed in one piece. As shown in this figure, the latch member is formed with a recess 56, in which the latch roller 46 is positioned in the closed condition of the switch. A nose portion 57 is provided which, in the upward movement of the latch to trip the switch, engages with said roller to move the toggle members from on center or straightened position, to thereby permit the movement of the switch into open position. The same movement of the latch serves to also withdraw the latch from engagement with the latch roller.
- In the closed position of the switch the toggle members are on center, and there is consequently no strain upon the latch, and the latch may therefore be operated with a minimum of energy.
- When the switch is subject to shocks or jars caused by the vibration of the switch supports by any means, such shocks or jars will not operate to open the switch. The latch may be permitted a small amount of movement, due to the shocks or jars, but is restricted from downward movement by the pin 15, and upward movement by engagement with the latch roller 42. The permitted amount of movement is so small that the force with which the nose portion 57 of the latch is brought into engagement with the latch roller 42 is insufficient to cause the movement of the toggle members beyond straight condition; and, moreover, the movement of the switch members is restricted by the engagement of the latch roller with the wall of the recess 56.
- A second stationary switch contact member is provided, with which that portion of the brush member disposed within the supporting standards is arranged to make contact in closed position of the switch. Said stationary contact member is composed of a single strip of sheet material, and is formed with substantially parallel side portions 58 and a flat connecting portion 59. Said side portions or walls 58 of the contact member are formed with slots or recesses 60 therein, in which are adapted to be arranged the base portions 12 of the supporting standard. The screw 14 is adapted to pass through an opening in one of said base portions 12, and to engage a threaded opening 61 in the stationary contact member, whereby said member is secured to the switchboard 9.
- Due to the disposition of said contact member about the base portion 12 of the supporting standards, said standards are also secured to the switchboard by the same screw 14. The flat top portion 59 of the stationary contact member forms a contact surface which is adapted to be engaged by the brush member 17 in the closed position of the switch.
- A pig tail or flexible braid 62 is secured by means of the screw 63 to the under side of the contact member, and extends through an opening 64 therein to the channel portion 16 of the movable switch arm, where it is clamped by means of bolts 28 between the strips 26 and 27. Said pig tail

forms an electric connection between the stationary contact member and the brush member 17, whereby sparking between the said members upon the opening of the 5 switch is obviated.

The flat portion of said contact member is formed with an extended ear 65, with which connection is adapted to be made between the stationary contact member and 10 the current coil of the overload tripping means.

The overload tripping means includes the L shaped core 66 formed of laminated strips of iron secured in the support 67, which is 15 formed of non-magnetic material, and is fastened by means of bolts 68 to the switchboard 9. Said support 67 is of channel section, and is formed with extended end portions 69, between which the movable element 20 70 of the tripping means is pivoted at 71. Said movable element 70 is formed of magnetic material of L shape, and its end portion 72 is arranged in proximity with an end of the stationary core 66.

25 Said stationary core 66 and movable member 70 in the actuated condition of the tripping coil, form a substantially rectangular magnetic circuit, which is incomplete at the pivotal end of the element 70 and at 30 the end 72 thereof. The end 74 of the core 66 is provided with a member 75 formed of non-magnetic material of channel section, and downwardly extended. Said member 75 is formed with a slot 76 in a face thereof, and an overload adjusting means is disposed therein.

Said overload adjusting means comprises a button 77 disposed on the outer face of 40 said member 75, and having a bolt or screw which projects through the slot 76 and is in engagement with a nut or plate 78 movably arranged within the channel portion of said member 75. Said adjusting means may be moved to any position in the slot 45 76 by partially rotating the button 77, whereupon said button becomes unclamped from said member 75, and can be moved to any desired position and reclamped in set position by the partial rotation of the button 77 in the reverse sense, which operates 50 to clamp the flat wall of said member 75 between the button 77 and nut or plate 78.

The end 72 of the movable element or armature 70 of the tripping means is provided with a projecting pin 79 secured therein, and which extends through the slot 76 of said member 75, and is movable therein. In the normal or insufficiently energized position of said armature or movable member 60 70, the pin 79 rests upon the nut or movable plate 78 of the trip coil adjusting means, and by a movement of said adjusting means along the slot 76, the armature 70 is moved nearer or farther away from the end 74 of

the core 66, and thereby varies the current 65 value at which the trip coil will be sufficiently energized to cause the movement of the armature 70 to trip the switch. The member 75 may be provided with a calibrated scale 80, whereby the setting of the 70 adjustment may indicate the value of current at which the overload tripping means will operate.

A strip 81 is secured by means of screws 82 to the armature 70 and extends under 75 the latch 44 of the circuit breaker. A tripping pin 82 of insulating material is secured to the end of said strip 81 by means of the nut 83, and is arranged beneath the latch 44, to be brought into contact there- 80 with in the operated condition of the tripping means to trip the latch and open the switch. A button 85 is secured to the armature 70, whereby said armature may be manually operated to cause the opening of 85 the switch independently of its opening because of an overload.

The current coil 86, as here shown, may be formed of a flat strip of material edge-wise wound upon an insulating bushing 87 90 and disposed over the core 66. An end 88 of said coil is secured by means of the screw 89 to the ear 65 of the stationary contact member and forms means whereby connection is made between said member to the 95 tripping coil. The other end 90 is arranged in a slot in the end of a rod 91, and may be secured therein by sweating and by rivets 92. Said rod 91 projects through the switchboard 9, and a washer 93 is disposed between 100 said switchboard and the end 90 of said coil 86, whereby said rod 91 forms one terminal of the switch or circuit breaker, of which the rod or stud 94, secured to the stationary contact member 20, is the other terminal.

Although the tripping coil is here shown as comprising a spirally wound strip and is adapted for comparatively high values of current, yet it is obvious that for trip coils 110 designed to operate between various ranges of current, the winding of the coil may be differently arranged in order to be the most effective for any particular range of current values. All coils are designed to be formed 115 independently of the magnetic frame and to be arranged thereon, whereby a single magnetic structure may serve for various coil windings.

I claim:

1. In an electric switch, the combination 120 with a movable switch member, and a supporting housing therefor comprising spaced-apart side-walls and spaced-apart side-wall connecting and supporting strips, of a stationary switch member disposed between said side-walls and having recesses therein 125 adapted to receive said connecting and sup-

porting strips, and means to secure said contact member to said housing and also secure said housing to a support.

2. In an electric switch, the combination 5 with a movable switch member, and a supporting housing therefor comprising spaced-apart side-walls and spaced-apart side-wall connecting and supporting strips, of a stationary switch member disposed between 10 said side-walls and having recesses therein adapted to receive said connecting and supporting strips, and means extending through one of said strips and engaging said stationary switch member to secure said 15 housing and stationary switch member to a support.

3. In an electric switch, the combination 20 of a supporting housing having spaced-apart side-walls and spaced-apart connecting-portions, and a stationary switch-member comprising a stamping having a flat top wall and side-walls with notches therein in which said connecting-portions of the housing are received.

25 4. In an electric switch, a movable switch member, a switch housing bearing said movable switch member having spaced-apart standards and cross connecting strips, a stationary contact member arranged within 30 said housing above said cross connecting strips, means engaging one of said cross connecting strips to secure said housing to a support, and means extended through another of said cross connecting strips and engaging said contact member to secure said member and said housing to the support.

5. In an electric switch, a switch housing, a movable switch member pivoted to said housing, a handle member pivoted to said 40 housing, toggle members connecting said handle member with said movable switch member, said handle member being formed with a projection cut and extended therefrom to engage said housing in the fully 45 closed position of the switch to limit further movement of the movable member.

6. In an electric switch, a switch housing having spaced standards, a pivot pin extended between said standards, a movable switch member pivoted on said pin, a handle member pivoted to said standards, toggle members connecting said handle member and said movable switch member, a latch roller pivoted to said handle member, and a latch pivotally disposed between said standards and engageable with said latch roller to cause a movement of the switch toward open position, said latch being formed with projections thereon engageable with said pivot pin, and said pin serving as a stop to limit the movement of said latch between normal and operated positions.

7. In an electric switch, a movable switch 65 member, means restraining said member in

closed position, and a tripping device for said switch including a substantially L-shaped core of magnetic material, a tripping coil on one of the legs of said core, a channel shaped member of non-magnetic material in which the other leg of said core is received, a substantially L-shaped armature pivoted at one of its legs to said member and movable relative to said core, a second channel shaped member in the channel 75 of which the other leg of said core is received, said member extended beyond said leg to receive said armature, a pin carried by said armature projecting through a slot in the extended portion of said second channel member, and a button adjustably arranged in said slot with which said pin is in normal engagement.

8. In an electric switch, stationary and movable switch-members, a threaded switch 85 stud having an axially-disposed slot in its end, and a tripping coil having a flat terminal fixed in the slot in said stud with its side-portions extended on opposite sides beyond said stud to form a shoulder adapted 90 to engage a support for the stud.

9. In an electric switch, a movable switch member, an operating member therefor connecting said members arranged on center to restrain the switch in closed position, a 95 latch to lock said toggle from movement beyond on center position in one direction and an abutment to lock said toggle from movement beyond on center position in the other direction.

10. In an electric switch, a movable switch member, an operating member therefor, mechanism connecting said members whereby a movement of said operating member serves to move said switch member 105 into closed position, said mechanism being arranged in such closed position of the switch, to be without tendency to independently move said switch member from closed position, a latch to lock said mechanism 110 from unintentional movement, a tripping member engageable with said latch to remove it from locking engagement with said mechanism and engageable with said mechanism to move it to cause the opening of the 115 switch, and means permitting independent movement of said latch and tripping member.

11. In an electric switch, a movable switch member, an operating member therefor, 120 mechanism connecting said members whereby a movement of said operating member serves to move said switch member into closed position, said mechanism being arranged in such closed position of the switch, 125 to be without tendency to move said switch member from closed position, a latch to lock said mechanism from unintentional movement, and a tripping member engageable with said latch to remove it from locking 130

engagement with said mechanism and engageable with said mechanism to move it to cause the opening of the switch.

12. In an electric switch, stationary and movable switch members, operating mechanism comprising toggle-members, means to restrain said toggle-members from movement in an overshot direction whereby to hold the switch closed, and a latch arranged
- 5 normally to hold said toggle members from movement in the opposite direction also ar-

ranged to release said toggle members and forcibly move them in the opposite direction to open the switch.

In testimony whereof, I have signed my name to this specification, in the presence of two subscribing witnesses.

DANIEL M. SCHIFFERT.
